CLAIM

The ornamental design for a shelving wall bracket as shown and described.

DESCRIPTION

FIG. 1 shows a right hand perspective view of the shelving wall bracket.

FIG. 2 shows a front elevation view thereof.

FIG. 3 shows a rear elevation view thereof.

FIG. 4 shows a left hand side elevation view thereof.

FIG. 5 shows a right hand side elevation view thereof.

FIG. 6 shows a top plan view thereof.

FIG. 7 shows a bottom plan view thereof; and,

FIG. 8 shows a right side perspective view of the shelving wall bracket in an environment of use.

The broken lines in FIG. 8 depict environmental structure and form no part of the claimed design.
